CAMP STOVE

Donn C. Hendee, 1773 Roslyn St.,
Denver, Colo. 80222

Filed Aug. 24, 1967, Ser. No. 8,376

Term of patent 14 years

(Cl. D81—10)

FIG. 3.

FIG. 4.

FIG. 5.

FIGURE 5 is an end view looking to the right in FIGURE 4. The appearance of the unit as seen from the opposite end is a mirror image of FIGURE 5 except that the valve and gas inlet are illustrated.

I claim:

The ornamental design for the camp stove, as shown and described.
